Patented Aug. 29, 1922.

William H. Fulper ^{Inventor}
By his Attorney
Mark J. Kent

UNITED STATES PATENT OFFICE.

WILLIAM H. FULPER, OF FLEMINGTON, NEW JERSEY.

DESIGN FOR A LAMP SHADE OR SIMILAR ARTICLE.

61,411.

Specification for Design.

Patented Aug. 29, 1922.

Application filed March 9, 1921. Serial No. 450,967. Term of patent 14 years.

To all whom it may concern:

Be it known that I, WILLIAM H. FULPER, a citizen of the United States of America, and resident of Flemington, county of Hunterdon, and State of New Jersey, have invented a certain new, original, and ornamental Design for a Lamp Shade or Similar Article, of which the following is a specification, reference being had to the accompanying drawing, forming part thereof.

In the drawing, the figure is an elevation of a lamp shade embodying my design.

I claim:—

The ornamental design for a lamp shade or similar article, substantially as shown.

WILLIAM H. FULPER.
